THREAD GRIPPER

Max Bär, Augsburg-Göggingen, Germany, assignor to "Knotex" Maschinenbau G. m. b. H., Augsburg-Stadtbergen, Germany, a corporation of Germany

Application May 9, 1951, Serial No. 225,449
In Germany May 10, 1950

7 Claims. (Cl. 28—49)

1

This invention relates to a thread gripper for warp knotting or tying machines.

The satisfactory function of the thread gripper by which the two threads to be knotted together are fed to the knotting tool, is of decisive importance for the knotting process and thus for the function of the entire machine. This satisfactory function of the thread gripper is impaired by the fibrous material detaching from the threads as the machine is operating.

It is an object of the present invention to provide a thread gripper which avoids this difficulty and is simple in construction and operation.

With this and further objects in view, which will hereinafter appear, according to the present invention the gripping jaws are arranged so as to be open on all sides, and the gripping surfaces themselves are designed to issue on their side facing away from the drawing-in side into an open space into which the deposited waste fibres are discharged by the thread as it is drawn in. Thus, the chance of deposition of loose fibres in the region of the gripping jaws is reduced to a minimum and it is ensured that the gripping jaws are kept free from obstructions which would impair their operation.

The invention will be better understood by reference to the following detailed description in connection with the accompanying drawing showing by way of example and purely schematically one embodiment of the invention and in which:

Fig. 1 is a side view of a thread gripper having the invention applied thereto;

Fig. 2 is an end view thereof; and

Fig. 3 is a section on line I—I of Fig. 1.

Referring to the drawing, it will be seen that the holder 1 of the thread gripper has a cylindrical guide 2 for its reciprocal motion, imparted to it by the link or lever 3. A recess 4 of the holder 1 rides on a key 22 of the guide bolt 21 so as to secure it against turning. The holder 1 has a central bridge portion 5 serving as a stationary abutment for the two gripping jaws 6 which are fulcrumed at 7 on a pin 8 after the manner of a balance beam, said pin protruding through a bore in the forked members 9 of the holder 1 and being acted upon, through the projections 10, by a blade spring 11 whose force can be adjusted by the knurled nuts 12 through stud bolts 13 fixed in the holder 1. Each gripping jaw 6 is shaped like a skid at its two ends and bears at its front end a projection 14 protruding into a slot 15 at the ends of the forked part 9. On the other side each gripping jaw 6 is

2

formed with a cheek 16 overhanging the abutment bridge 5 laterally of the gripping jaws. Said jaw is recessed at 17 to form the thread contact surfaces. These recesses 17 therefore will determine the position of the thread directly opposite the fulcrum 7 and accordingly the point of attack of the spring force.

Inserted between the lever 3 and the fulcrum 20 of the holder 1 is a lever 18 having a handle 19 by which it can easily be swung out of the fulcrum point 20.

It will thus be seen that the thread contact surfaces are formed by recesses in cheeks of the gripping jaws which cheeks are arranged laterally of the gripping surfaces. The gripping jaws are advantageously in the shape of skids or skis. Thus, contrary to the known devices, they do not form a collecting or partition wall for the waste fibres. Moreover the recesses define the position of the thread towards both sides, whereby a particularly reliable gripping position is ensured.

The construction of the thread contact surfaces according to the present invention offers the possibility, in case of gripping jaws suspended after the manner of a balance beam, to arrange the suspension at a point on the other side of the recesses forming the thread contact surfaces. This offers the advantage that the thread is held at the point of the most intensive clamping pressure and that an absolutely safe clamping position for the thread is obtained, which of course forms an edge-shaped support permitting adaptation of the clamping jaw in any position.

In order to knot threads of different thickness according to a further feature of the present invention two clamping jaws are arranged on both sides of a solid abutment serving simultaneously as a separating bar, whereby the whole construction of the thread gripper is simplified compared to the conventional type. The size of the thread gripper is further reduced and made more compact by arranging the gripping jaws within a fork accommodating the movable guide of its balance beam support and provided on its outer side with springs, more particularly blade springs, for producing the clamping pressure. By this position of the blade springs it is easily possible to adjust their spring force by normally operable set nuts or set screws or to interchange them for heavier springs. By the engagement of the guide projections of the clamping jaws on their draw-in side in slots of the forked ends the clamping jaws are simultaneously protected

against angular displacement. These slot guides are self-cleaning, so that soiling is prevented.

Although being efficiently protected against premature soiling and disturbances, my novel thread gripper also has to be cleaned from time to time. To facilitate this cleaning, it may be loosely engaged on the guide member serving for its reciprocal motion and moreover it may be adapted to be easily disengaged from its driving lever.

While the invention has been described in detail with respect to a now preferred example and embodiment of the invention it will be understood by those skilled in the art after understanding the invention that various changes and modifications may be made without departing from the spirit and scope of the invention and it is intended, therefore, to cover all such changes and modifications in the appended claims.

What is claimed is:

1. A thread gripper for warp knotting machines, comprising a pair of gripping jaws which are open on all sides, means for suspending said gripping jaws after the manner of a balance beam, a movable guide for the suspension means, a bifurcated member accommodating said movable guide, and springs disposed on the outer side of the bifurcated member for producing the gripping pressure.

2. Thread gripping mechanism for warp tying apparatus comprising a gripping jaw, an abutment adjacent said jaw, gripping surfaces on said jaw for holding thread to be tied against said abutment, spring means yieldably urging said jaw against said abutment, means for reciprocating said jaw and said abutment toward and away from thread to be gripped, said gripping surfaces having a thread inlet side, portions of said jaw and said abutment on the opposite side thereof from said inlet side defining an unobstructed discharge opening for substantially complete ejection in each gripping operation of waste fibers accumulated at said gripping surfaces during a previous gripping operation.

3. Thread gripping mechanism for warp tying apparatus comprising a pair of gripping jaws, a stationary abutment coacting with said jaws, means for pivotally mounting said jaws on opposite sides of said stationary abutment, a recess on said jaws forming gripping surfaces thereon, means for urging said gripping surfaces yieldably against said abutment, said urging means and said mounting means coacting for admitting at one side of said jaws thread to be gripped, and portions of said jaws and said abutment at the side opposite to said admitting side defining a substantially unobstructed discharge space for ejection of waste fibre accumulating at said gripping surfaces as thread is inserted therein.

4. Thread gripping mechanism for warp tying apparatus comprising a curved gripping jaw substantially open on all sides, a stationary abutment adjacent one edge of said jaw, one curved edge of said jaw partially overlying said abutment, a thread-receiving recess in said overlying edge, gripping surfaces on said jaw and said abutment for gripping thread inserted therebetween through said recess, means for pivotally mounting said jaw adjacent said abutment, means for urging gripping surfaces on said jaw yieldably against said abutment, said curved jaw and said

5 abutment forming on one side of said recess a thread inlet to said gripping surfaces, and portions of said abutment and said jaw on the opposite side of said recess from said inlet side defining a discharge space for substantially complete ejection in each gripping operation of waste fiber accumulating between said gripping surfaces in a previous gripping operation.

10 5. Thread gripping mechanism for warp tying apparatus adapted to grip two threads to be tied comprising two oppositely disposed gripping jaws, a stationary abutment between said jaws adapted to be inserted between said two threads to be gripped, means for yieldably urging each of said jaws inwardly toward said abutment, a thread receiving recess on each said jaw at the side thereof adjacent said abutment, gripping surfaces on said jaws and said abutment at said recesses, one side of said jaws being outwardly curved forming on each side of said abutment 15 a thread entrance to said gripping surfaces, the opposite side of said jaws being outwardly curved forming on each side of said abutment a substantially unobstructed discharge space for ejection of waste fiber from between said gripping surfaces.

20 6. Thread gripping mechanism for warp tying apparatus comprising a three prong frame member having the center prong adapted to be inserted between threads to be gripped, a pair of gripping jaws, means for pivotally mounting said jaws on the outside prongs of said frame member on opposite sides of said center prong, spring means for yieldably urging said jaws inwardly 25 against opposite sides of said center prong, means for adjusting tension of said spring means, a bifurcation at the outer end of each outside prong, guide means on said jaws engaging said bifurcation, gripping surfaces on said jaws at the edge opposite to said pivotal mounting engaging cooperating gripping surfaces on opposite sides of said center prong, one side of said jaws adjacent said guide means being outwardly curved forming on each side of said center prong 30 a thread receiving entrance to said gripping surfaces, and the opposite side of said jaws being outwardly curved forming on each side of said center prong a substantially unobstructed discharge space for ejection of waste material from between said gripping surfaces.

35 7. In thread gripping mechanism for warp tying apparatus the combination comprising a movable gripping jaw, a stationary abutment coacting with said jaw, gripping surfaces on said jaw and said abutment for holding thread inserted therebetween, sliding means for mounting said mechanism for reciprocating motion toward and away from said thread to be gripped, lever means connected to a source of mechanical power for reciprocating said mechanism along said sliding means, and means for releasably engaging said lever means with said mechanism for selectively engaging or disengaging said mechanism from said source of power.
